EYELASH CURLER

William R. Tuttle and Charles W. Stickel,
Rochester, N. Y.

Application July 13, 1939, Serial No. 284,156

19 Claims. (Cl. 132—32)

Among the objects of the present invention is the provision of a novel eyelash curling structure constituting an improvement over that disclosed and claimed in Patents Nos. 1,699,084 granted January 15, 1929, and 2,022,697 granted December 3, 1935.

In the utilization of eyelash curlers or crimpers constructed in accordance with the above identified patents it has been found that as the relatively movable jaw is vertically reciprocated, the vertical arm engaging portions or movable sleeves on the end of said jaw tend to irritate the skin of the face of the user, and also to catch between the said portions or sleeves and the parallel arms upon which they ride facial hair from the user's cheek, causing pain, and being otherwise undesirable.

One of the objects of the present invention is the provision of a structure whereby the user's face is protected specifically from the movable vertical arm engaging portions or sleeves associated with or on the end of the movable jaws, and whereby in normal use no moving parts may contact the user's face.

Another object herein is the provision of such face shielding structure which is low in material cost and which may be affixed to the curler with a minimum amount of labor.

A still further object herein is the provision of a novel combination of eyelash curler and shielding means therefor which is extremely simple in construction so that said shielding means may be incorporated with curlers made in accordance with the above identified patents, and which will require a minimum amount of change in such curlers for the accommodation of the installation of the shields thereon.

Another object of the present invention is the provision of shielding means for an eyelash curler which will enhance the appearance of the device, and generally aid in producing a resulting streamlined contour.

These objects and other incidental ends and advantages will more fully appear in the progress of this disclosure and as pointed out in the appended claims.

Accompanying this specification and forming a material part of this disclosure are drawings showing two embodiments of the invention herein and wherein similar reference characters designate corresponding parts throughout the several views, in which:

Fig. 1 is a rear elevational view of the first embodiment of the invention, with the movable or

lower jaw in the elevated or closed position thereof.

Fig. 2 is a side elevational view of Fig. 1 as seen from the right side thereof.

Fig. 3 is a front elevational view of the first embodiment of the invention or as viewed from the rear of Fig. 1.

Fig. 4 is a side elevation view, slightly reduced in scale, taken similarly to Fig. 2 and showing the lower or movable jaw in the lowered or open position thereof.

Fig. 5 is an enlarged sectional view as seen from the plane 5—5 on Fig. 2.

Fig. 6 is a top plan view as seen from the plane 6—6 on Fig. 2.

Fig. 7 is an enlarged fragmentary side elevational view, taken similarly to the upper portion of Fig. 2 but showing a second embodiment of the invention.

Fig. 8 is an enlarged fragmentary front elevational view of the second embodiment of the invention as seen from the right side of Fig. 7.

Fig. 9 is an enlarged fragmentary sectional view as seen from the plane 9—9.

Turning now to the first embodiment of the invention illustrated in Figs. 1 to 6 inclusive, the eyelash curler generally indicated by numeral 30 comprises a relatively stationary element 31 and a relatively movable element 32. The stationary element comprises juxtaposed members 15 and 16, the finger loop 17, flattened portions 15' and 16', bifurcating posts 18 and 19 and vertical and parallel arms 18' and 19'. Connecting the two upper ends of the parallel arms 18' and 19', is a curved stationary upper jaw 23.

The relatively movable element 32 comprises juxtaposed members 10 and 11; the finger loop 12; flattened portions 13 and 14; a relatively U-shaped member 33 having lower arms 24 and 25; upper offset arms 26 and 27, and a horizontally disposed portion 34. The upper ends of the offset arms 26 and 27 are fixedly connected to the under surface of the lower movable jaw 20 which is suitably grooved or dished to have secured therewithin the resilient facing 22.

The horizontal portion 34 loosely penetrates two orifices in the upper ends of the members 10 and 11 serving thereby to pivotally connect said members to the U-shaped member 33 which is reinforced by means of the crossbar 28 which is attached to the arms 26 and 27 by means of the knuckle reinforcements 28'.

The flattened portions 13 and 14 are disposed between the flattened portions 15' and 16' and

are pivotally interconnected thereat by means of a pin 29.

The outer ends of the movable jaw 20 are provided with orificed vertical arm engaging portions constituting the integral short sleeves 21. The sleeves 21 are adapted for slidable movement longitudinally of the arms 18' and 19', and this occurs when the finger loops 12 and 17 are moved toward or away from each other.

The outer ends of the stationary jaw 23 are affixed to the upper ends of the parallel arms 18' and 19', the inner and opposite portions of the upper ends of said arms being flattened thereat to receive the ends of the stationary jaw. Attachment of the ends of the jaw to the ends of the arms may be made in any suitable manner as for example, by spot welding or preferably by riveting the parts together by means of integral rivets extruded from the upper ends of the arms at the time the same are flattened preparatory to the connection thereto of the ends of the stationary jaw.

A pair of shields generally indicated by numerals 35 and 36 are irregularly shaped and the configuration thereof is best seen by a reference to the several figures in the drawings.

Each of the shields is provided with a central semi-cylindrical portion 37 and 38 which is of a sufficient diameter, and is sufficiently laterally displaced to permit adequate clearance between itself and the vertical and parallel arms 18' and 19' to allow the sleeves 21 to move freely therebetween. The upper clamping portions 39 and 40 are relatively reduced in diameter as compared with the central portions 37 and 38 and extend completely around the upper terminals of the arms 18' and 19' and the outer ends of the stationary jaw 23, and the portions 39 and 40 are further provided with closed tops 41 and 42 which cover the top ends of the arms 18' and 19'. These tops are best seen in Fig. 6.

The shields 35 and 36 are provided with lower clamping portions 43 and 44 which are reduced in diameter with relation to the central portions 37 and 38 and which are wrapped about the bifurcating posts 18 and 19.

The shields 35 and 36 are preferably made of metal of such gauge and hardness that the compressing of the clamping portions 39, 40 and 43, 44 about the arms 18' and 19', and the bifurcating posts 18 and 19 respectively will secure and maintain the shields in operative position. As will appear to those skilled in the art to which the present invention relates, other means for securing the clamping portions may be utilized as for example, soldering or riveting. It has been found however, that a smoother and cheaper connection of the shields to the eyelash curling device may be secured by crimping or clamping rather than such other methods. It will be noted that the lower clamping portions 43 and 44 are bent inwardly of the curling device toward each other so that they will more readily conform to the configuration of the bifurcating posts 18 and 19 and the parallel arms 18' and 19'.

The shields 35 and 36 adjacent the central portions 37 and 38 are cut away or open and the length and positioning of these cutaway portions is such that at no point during the normal operation of the eyelash curling device do the sleeves 21 contact the shields 35 and 36. This feature is clearly shown in Figs. 1, 2 and 4 of the accompanying drawings in which the movable jaw 20 is shown at its uppermost position in Figs. 1 and 2 and at its lowermost position in Figure 4. This

freedom of movement of the sleeves 21 is very important in the smooth and regular operation of the eyelash curling device 30.

Turning now to the second embodiment of the invention illustrated in Figs. 7, 8 and 9, it is seen that the second embodiment presents many points of similarity to the first embodiment.

The principal difference between the two embodiments lies in the provision in the second embodiment of means which tend to prevent any longitudinal slippage or movement of the shields 35'' and 36'' along the bifurcating posts 18'' and 19'' and the parallel arms 18''' and 19'''. The arms 18''' and 19''' are provided with indentations, notches or grooves 46; while the bifurcating posts 18'' and 19'' are provided with indentations, notches or grooves 48. The indentations 46 and 48 are preferably made so as to have their principal direction disposed at right angles to the length of the arms and posts respectively. When the shields 35'' and 36'' are installed upon the eyelash curling device, the upper and lower clamping portions 39'' and 40'' and 43'' and 44'' are pressed so that they conform to the shape of the indentations 46 and 48 and thus have corresponding indentations 50, 51, 52 and 53.

In both of the embodiments of the invention it will be noted that the clamping portions, both upper and lower, are connected to the central portions of the shields by means of gently sloping or curved portions which are best seen in Fig. 7 of the accompanying drawings and as there indicated by numerals 54 and 55. These curved portions lend a more streamlined and otherwise desirable appearance to the shields and hence, the eyelash curling device with which they are combined and serve a functional purpose in that they prevent any sharp or rough portions of the eyelash curling device from contacting the cheek or face of a person using the device.

Operation

It may be readily seen that the present combined shields and eyelash curling device may be operated in a manner similar to the eyelash curling device without the shields. Among the advantages presented by the present invention is that as the vertical and parallel arms (18', 19'; 18''', 19''') are placed toward the face the shields 35, 36 and 35'' and 36'', automatically become interposed between these arms and the face so that the sleeves 21 and 21'' are prevented from rubbing across the face of the user and catching facial hairs between said sleeves and said arms. Thus no moving parts of the eyelash curling device are allowed to come into contact with the face of the user.

Furthermore, by resting the shields against the face of the user, the entire device may be steadied and made more stationary so that the eyelashes may be more readily retained in proper position between the stationary and movable jaws as the movable jaw is closed against the stationary jaw with the eyelashes therebetween.

It may thus be seen that there have been disclosed two embodiments of a novel eyelash curling device and shield combination possessing definite advantages in the use thereof, and a novel advantageous structure which accomplishes the desirable purposes set forth hereinabove with a minimum of parts and with a minimum of cost in the fabrication and installation thereof.

We claim:

1. An eyelash curling device including a vertical arm; a movable jaw having a vertical arm en-

gaging portion, said portion being slidable along said vertical arm; and means associated with the vertical arm to shield said movable arm engaging portion from contact with the face of the user when said jaw is moved during the normal operation of the device.

2. An eyelash curling device including a vertical arm; a movable jaw having a vertical arm engaging portion, said portion being slidable for a predetermined distance along said vertical arm, 10 said distance constituting a normal path of travel of said portion; and means associated with the vertical arm to shield said arm engaging portion from contact with the face of the user when said jaw is moved during the normal operation of the 15 device, said means being connected to said arm at a point beyond the normal path of travel of said movable jaw.

3. An eyelash curling device including a vertical arm having a transverse indentation therein; a 20 movable jaw having a vertical arm engaging portion, said portion being slidable along said vertical arm; a shield connected to the vertical arm and having a transverse indentation interlocking with the indentation in said arm, said shield acting to prevent said arm engaging portion from 25 contacting the face of the user while the device is in operation.

4. An eyelash curling device including a vertical arm; a movable jaw including an integral short sleeve at an end thereof; said sleeve being movable along said vertical arm and means associated with the vertical arm to shield said sleeve from contact with the face of the user when said jaw is moved during the normal operation of the 30 device.

5. An eyelash curling device including a vertical arm; a movable jaw having an orificed end portion constituting an integral short sleeve slidable along 40 said vertical arm for a predetermined distance on said arm and which is the normal path of travel thereof; and means associated with the vertical arm to shield said movable sleeve from contact with the face of the user when said jaw is moved during the normal operation of the device, said means being connected to said arm at a point beyond the normal point of travel of said movable sleeve.

6. An eyelash curling device including a vertical arm having a transverse indentation therein; a movable jaw having an orificed portion in the form of an integral short sleeve slidable along said vertical arm; a shield connected to the vertical arm and having a transverse indentation engag-

ing the indentation on the arm; said shield acting to prevent said sleeve from contacting the face of the user while the device is in operation.

5 7. An eyelash curling device including a vertical arm; a movable jaw having a vertical arm engaging portion movable along said vertical arm; and means associated with the vertical arm to shield said arm engaging portion from contact with the face of the user when said arm engaging portion is moved during the normal operation of the device; said means including a shield comprising a central portion spaced from said vertical arm and upper and lower clamping portions engaging said vertical arm.

8. An eyelash curler device including a vertical arm; a movable jaw having a vertical arm engaging portion movable along said vertical arm; and means associated with the vertical arm to shield said movable arm engaging portion from contact with the face of the user when said arm engaging portion is moved during the normal operation of the device; said means including a shield comprising a semi-cylindrical central portion spaced from said vertical arm and upper and lower clamping portions engaging said vertical arm.

25 9. An eyelash curling device including a vertical arm; a stationary jaw affixed at the end thereof to the upper end of said vertical arm; a movable jaw adapted for relative movement toward and away from said stationary jaw and having an arm engaging portion slidable along said vertical arm, and means associated with the vertical arm to shield said arm engaging portion from contact with the face of the user when said jaw is moved during the normal operation of the device, said means including a shield comprising a central portion adapted to contact the face of the user and spaced from said vertical arm and upper and lower clamping portions, the upper clamping portion engaging the upper end of the vertical arm and the lower clamping portion engaging said vertical arm.

10. An eyelash curling device including a pair 45 of vertical arms; a stationary jaw attached at its ends to the upper ends of said vertical arms; a movable jaw having orificed ends slidable along said vertical arms, and means associated with each of the vertical arms to shield the ends of the movable jaw from contact with the face of the user when said jaw is moved during the normal operation of the device.

CHARLES W. STICKEL.
